(57) **CLAIM**

The ornamental design for a brake disc rotor, as shown and described.

DESCRIPTION

FIG. 1 is a front, right side perspective view of a brake disc rotor;

FIG. 2 is a top plan view of the brake disc rotor, where the bottom plan view, the first side elevation view and the second side elevation view are identical to the top plan view;

FIG. 3 is a front elevation view of the brake disc rotor;

FIG. 4 is a front, right, bottom perspective view of the brake disc rotor; and,

FIG. 5 is a rear, right, top perspective view of the brake disc rotor.

The broken lines depict portions of the brake disc rotor which form no part of the claimed design.
